UNITED STATES PATENT OFFICE

FRANCIS W. WILLIAMS, OF CHARLOTTE, NORTH CAROLINA

HEAT EXCHANGE DEVICE

Application filed May 20, 1929. Serial No. 364,490.

This invention relates to a heat exchange device, and more especially to a device for cooling water which is desired to be used for ice making, and also for cooling any other fluid which may be desired to be passed through the machine.

An object of my invention is to provide a heat exchange device in which a plurality of pipes are adapted to pass a refrigerating agency through a series of troughs and said troughs are adapted to receive the fluid which is adapted to be cooled and to convey the fluid from one trough to another, and to allow the fluid to fall into a vat from whence it is taken to be used.

Another object of my invention is to provide a heat exchange device in which a fluid is passed through a plurality of pipes and said pipes are submerged in a plurality of troughs, with means for retarding the flow of the fluid desired to be cooled through the troughs, together with means for permitting the troughs to be entirely emptied when not in use, and said emptying operation to be entirely automatic, and also to provide means for automatically stopping the flow of the refrigerating fluid when the water in the tank below the machine reaches a predetermined temperature degree, together with means for automatically controlling the flow of water, said flow of water being controlled by the level of the water or any fluid which is desired to be refrigerated and which rest in the tank below the heat exchange device.

Some of the objects of my invention having been stated other objects will appear as the description proceeds when taken in connection with the accompanying drawings, in which—

Figure 1 is a side elevation partially in cross-section of my heat exchange device;

Figure 2 is a view taken along the line 2—2 in Figure 1;

Figure 3 is a view taken along the line 3—3 in Figure 2;

Figure 4 is a cross-sectional view taken along the line 4—4 in Figure 2;

Figure 5 is a detail view of the means for connecting the three pipes together at each end of the heat exchange device.

Referring more particularly to the drawings the numeral 10 indicates a box member in which my device is adapted to be placed for operation, the ends of said box member being designated by the reference characters 11 and 12 and the side portion of said box member being designated by the reference character 13, only one of said side portions being shown in Figure 1 but the side opposite to the side 13 is identical to the said side 13. I provide a tank member 15 which has the end members 16 and 17 and the side member 18. This tank has a metallic lining 19 and the metallic covering 20 therearound with sheets of cork 21 between said metallic members to provide an insulated tank for preserving the low temperature of the water.

In the bottom of the tank I mount the pipe 22 which is the outlet pipe through which the refrigerated liquid can be drawn for use. This pipe is secured to the bottom of the tank by means of the threaded flange member 23 being secured in place by means of the bolts 24. The bottom member 25 of the box in which my device is adapted to operate has the hole 26 therein through which the pipe 22 is adapted to pass. It is evident that this tank and the machine which is mounted therein can be lifted out of the box member if desired. Secured to the side portion of the tank 15 are the four upstanding members 30, 31, 32 and 33 which members are adapted to support the troughs into which the water or other liquid which is desired to be refrigerated is poured and passed therethrough. These members 30 to 33 inclusive have a plurality of bolts, which are in-

dicated by the reference character 35, passing therethrough, and on these bolts the troughs 36, 37, 38, 39, 40, 41 and 42 are adapted to rest in approximately a level position. A plurality of pipes are adapted to be mounted in said troughs. The pipe 50 is lead through the side of the tank at the bottom of the machine and branches outwardly by means of the members 51, 52 and 53 and the three pipes 54, 55 and 56 are connected to this pipe 50 and these pipes 54, 55 and 56 are lead through one trough and then up through another trough and so on until they reach the top of the machine where they are joined together by exactly the same mechanism as is shown in Figure 5 and has previously been described, and the pipe 58 leads the refrigerating fluid back to the source from which it came such as a compressor. Each of these troughs have one closed end and one open end, and in the open end of each trough there is a device for retarding the flow of water through each of the troughs and to cause the pipes to be entirely submerged by the water or the fluid which is desired to be refrigerated at all times. This retarding device comprises the members 60 and 61 which are hollowed out to fit around the pipes and the gasket member 62 is adapted to be placed between these members 60 and 61 to pass around the top portions of each of the pipes and the gasket member 63 is adapted to also be placed between the members 60 and 61 and to pass around the lower faces of each of the pipes, and then the gasket member 64 is adapted to be placed between the members 60 and 61 and the trough member. The bolts 65 and 66 pass through the members 60 and 61 and the gasket members 62 and 63 and also through the bottom of the trough member and thus firmly secures this retarding device in position, and prevents water or other fluid which is being refrigerated from passing out of the end of the trough except over the top, and the top of this retarding device being above the upper surface of the pipes causes the water or other fluid which is desired to be refrigerated to cover the pipes at all times. Each of the troughs have a plurality of holes 67 therein which permit each of the troughs to drain when operation of the machine ceases. The end of the troughs have the gasket member 64 extending slightly above the top of the retarding device 61 so as to prevent water from leaking between the head on the bolt and the wall portions of the trough so as to cause the water to fail to fall over the retarding device near the wall portion, and the wall portions of the trough have the inwardly curved portions 70 and 71 which direct the water inwardly so that it will fall entirely into the next preceding trough below without any falling over the

side of the next proceeding trough below.

These members 30 to 33 inclusive are braced together by means of the brace members 72 and 73.

The water or other fluid which is desired to be passed through my machine for purposes of refrigerating the same is conducted to the top of the machine by means of the pipe 74 and the valve 75 is located in said pipe with the rod 76 extending downwardly from said valve with the float 77 on the lower end thereof, the purpose of this arrangement being to operate the valve 75 by means of the float member 77 so that when a predetermined level is reached in the tank 15 that the flow of water will be automatically shut off or diminished as the case may be.

I also provide the thermostatic switch 80 in the vat with the wires 81 and 82 leading upward therefrom which wires are lead to the electric motor operating the compressor for forcing the refrigerating fluid through the machine so that when a predetermined degree of temperature is reached in the refrigerated fluid which falls into the tank 15 that the device will be automatically closed and the refrigerating fluid will not be passed through the pipe until the temperature rises to a predetermined point at which time the thermostatic switch will automatically start the compressor into operation and the machine will again function to pass the refrigerating fluid through the machine.

In the drawings and specification I have set forth a preferred embodiment of my invention, and although specific terms are employed they are used in a generic and descriptive sense only, and not for purposes of limitation, the scope of the invention being set forth in the appended claims.

I claim:

1. In a heat exchange device, a plurality of troughs mounted one above the other, said troughs being in the same vertical plane and being parallel to each other, said troughs being adapted to receive a fluid to be refrigerated, said fluid being adapted to pass from the end of one trough and to fall into the end of another trough, and so on through the series, a coil passing through each of the troughs and being bent after leaving one trough to follow the course of the next preceding trough respectively, a retarding member in the open end of each of the troughs adapted to retard the flow of the fluid adapted to be refrigerated until the fluid has covered the coil in the trough, and a plurality of holes in the bottom of each trough adapted to permit the trough to drain when the machine is not in operation.

2. In a water cooling machine, a plurality of troughs placed one above the other and one trough being adapted to empty into the next succeeding trough therebelow, a coil of pipes adapted to be passed up through all

of the troughs and being bent after leaving one trough to enter the next succeeding trough above, said coil of pipes being adapted to have conveyed therethrough a refrigerating fluid, each of said troughs in its discharge end having a retarding dam which is adapted to cause the level of the fluid to be refrigerated to rise above the pipes before falling from one trough into the next succeeding trough below, and means on the side of the trough for directing the falling fluid away from the edges of the next succeeding trough therebelow.

In testimony whereof I affix my signature.

15 FRANCIS W. WILLIAMS.
